UNITED STATES PATENT OFFICE.

MILTON W. HAZELTON, OF NEW YORK, N. Y., ASSIGNOR OF ONE-HALF TO
E. S. T. KENNEDY, OF SAME PLACE.

STEAM-BOILER.

SPECIFICATION forming part of Letters Patent No. 310,891, dated January 20, 1885.

Application filed March 6, 1884. Renewed December 15, 1884. (No model.)

To all whom it may concern:

Be it known that I, MILTON W. HAZELTON, a citizen of the United States of North America, and a resident of the city, county, and 5 State of New York, have invented a new and useful Improvement in Steam-Boilers, of which the following is a specification.

This invention is designed as an improvement 10 on the boiler for which Letters Patent No. 247,910 were issued to me October 4, 1881; and its object is to provide a boiler especially adapted to deliver dry 15 or superheated steam.

The invention consists in the combination, 20 with a boiler, preferably of the upright type, and forming part thereof, of a series of tubes radiating into the hot-air chamber from the steam-chamber of the boiler, and having their outer ends closed, and of series of open-ended 25 smaller tubes radiating from the steam-delivery pipe into the steam-chamber tubes, whereby very extensive steam heating or drying surface is secured.

Reference is to be had to the accompanying 30 drawings, forming part of this specification, in which similar letters of reference indicate corresponding parts in all the figures.

Figure 1 is a partly-sectional side elevation 35 of my improved boiler. Fig. 2 is a sectional plan of the same on lines xx , Fig. 1.

In the drawings, A represents the upright 40 boiler-cylinder, provided with man-holes a . B represents the feed-water pipe, and B' the blow-off pipe and cock.

From about on a level with the roof of the 45 fire-box C, nearly to the water-line b of the boiler, the space within the boiler-inclosing walls or shell D is filled with series of tubes E, closed at their outer ends and radiating 50 from the cylinder A in successive planes, one above the other, the tubes and spaces of the several series alternating with each other, as indicated in Fig. 2. From the steam-chamber A' of the boiler other series of tubes, F, closed 55 at their outer ends, radiate in successive planes one above the other. The steam-delivery pipe G is fixed with its vertical leg in the longitudinal axis of the steam-chamber, and with its horizontal leg extending out 60 through a side of the steam-chamber, its end

within said chamber being closed, as shown at c, Fig. 1. From the vertical leg of this steam-pipe G a series of open-ended tubes, H, radiate in successive planes and enter the tubes F, so that the steam must enter the 55 tubes F from the steam-chamber A', and then pass into the tubes H, and thence into the steam-pipe G, before escaping from the boiler. By this arrangement it will be seen that the steam, before escaping, is subdivided into 60 many distinct and individual columns or jets, that are separately exposed in the tubes F to the heat of the products of combustion as they pass up through the hot-air chamber from the fire-box C. These tubes F H may 65 be indefinitely multiplied, and may be arranged, in combination with the steam-delivery pipe, to apply to boiler steam-chambers of other forms of construction than that herein shown, the purpose being to apply them in 70 sufficient numbers and of sufficient dimensions to enable the steam to absorb and thereby to make use of a very considerable portion of the heat that would otherwise escape up the smoke-stack. In this instance the boiler- 75 inclosing walls D are designed to be prolonged into the boiler-flue or smoke-stack, and the side opening, K, may be made available for conveniently getting at the boiler for inspection and repairs; but the walls D may be 80 closed in at the top and a smoke-pipe may be inserted in the opening K.

I am aware that there are many steam 85 heating and drying devices in use, but know of none so effective and at the same time so simple as this.

Having thus described my invention, I claim as new and desire to secure by Letters Patent—

1. The combination, with the steam-chamber of a boiler and the steam-delivery pipe 90 closed at its inner end, of a series of tubes with closed outer ends radiating from the steam-chamber into a hot-air chamber, and a series of smaller open-ended tubes radiating from the steam-delivery pipe into the said 95 steam-chamber tubes, substantially as and for the purposes set forth.

2. The method substantially as herein described of drying or superheating steam, consisting in subdividing the mass of steam into 100

many distinct and individual columns or jets and exposing them to heat by causing the steam from the steam-chamber to enter a series of tubes radiating therefrom, and then to pass 5 into tubes that radiate from the steam-delivery pipe into the steam-chamber tubes, and thence into the steam-delivery pipe, said steam-chamber and the tubes radiating therefrom being exposed to heat in a hot-air chamber, as 10 set forth.

In testimony that I claim the foregoing as my invention I have signed my name, in presence of two witnesses, this 19th day of February, 1884.

M. W. HAZELTON.
